CONTROL ARRANGEMENT FOR ELECTRIC CIRCUIT BREAKERS

Alexander C. Boisseau and John W. Beatty, Lansdowne, Pa., assignors to General Electric Company, a corporation of New York

Application November 30, 1944, Serial No. 565,833

13 Claims. (Cl. 175—294)

1
Our invention relates to a control arrangement for electric circuit breakers, and particularly to a control arrangement for electric circuit breakers which are designed for reclosing operation.

Of recent years air blast circuit breakers employing the so-called retractable pin type contacts have been used extensively. The retractable pin type contacts form the arcing contacts and of course reclose as soon as the air blast is shut off. For this reason this type of circuit breaker employs disconnecting or isolating contacts connected in series with the arcing contacts which disconnecting contacts are sequentially operated with the arcing contacts to maintain the circuit in the open condition once it has been interrupted, even when the arcing contacts reclose.

Such circuit breakers lend themselves very well for reclosing operation, for reclosing will automatically occur if the isolating contacts are not operated. Our invention is particularly concerned with a control arrangement for the above-mentioned type of fluid blast circuit breakers and is furthermore concerned with a pneumatic reclosing relay which is adapted to be used with other forms of reclosing circuit breakers.

In retracting contact type breakers, the blast of fluid that is released, for example, in response to an abnormal line condition, first opens the arcing contacts thereby drawing an arc, then blasts the arc to extinction, after which it should maintain the contacts open for a brief period following interruption thereby preventing a possible restrike due to a high rate of rise of recovery voltage. Furthermore, should the contacts reclose while the abnormal line conditions still prevail, a successive blast should be initiated, in like manner to the preceding one; but in this event a somewhat longer blast may be required so that the arcing contacts are prevented from reclosing until the disconnecting contacts have separated sufficiently to effect a safe isolating gap in the line circuit. Obviously then, the blast durations are required to be precisely timed so that at least a sufficient amount of fluid is released, while, on the other hand, no more than an adequate amount should be released to fulfill the above requirements, because any unnecessary prolongation of the blast becomes excessively wasteful of pressure fluid.

2
Known methods for timing and sequentially operating the blast valve and the arcing and isolating contacts for performing a reclosing and subsequent tripping operating cycle involve vaguely timed or complicated interlocking relaying devices that are liable to cumulative inaccuracies.

Accordingly, it is an object of our invention to provide a new and improved reclosing control arrangement for electric circuit breakers.

It is another object of our invention to provide a pneumatic reclosing relay arrangement for electric circuit breakers, which is simple and compact, inexpensive to manufacture, and which gives accurate and positive control in every respect.

In the improved control arrangement of our invention, the pneumatic relay provides a unitary device that precisely governs and times with inevitable sequence the reclosing of the blast valve to effect the reclosing of the arcing contacts, the opening of the control circuit for an isolating switch interlock device, and the establishment of an alternate reopening circuit for the blast valve so as to effect the second interruption of the line and the subsequent opening of the isolating contacts.

Further objects and advantages of our invention will become apparent as the following description proceeds and the features of novelty which characterize our invention will be pointed out with particularity in the claims annexed to and forming a part of this specification.

For a better understanding of our invention, reference may be had to the accompanying drawing in which Fig. 1 is a schematic diagram, partly in section, of a reclosing control arrangement embodying our invention with the circuit breaker in the closed position, and Fig. 2 is a schematic diagram of a portion of Fig. 1 illustrating the position of certain elements of our invention at a predetermined point during the reclosing cycle.

Although our invention is applicable to any fluid operated circuit breaker, we have chosen to specifically illustrate our invention in Fig. 1 as applied to an electric circuit breaker of the fluid operated, fluid blast type such as is disclosed in the copending application, Serial No. 565,834, now Patent No. 2,450,628, Boisseau, Beall, Frank and Lowery, filed concurrently with

the present application and assigned to the same assignee as the present application. Although a polyphase circuit breaker has been shown in the copending Boisseau, Beall, Frank and Lowery application referred to above we have chosen, for the purpose of simplifying the disclosure, to illustrate our invention in connection with a single phase circuit breaker or one pole of a polyphase circuit breaker.

Referring now to Fig. 1 of the drawing, there is illustrated an electric circuit breaker generally indicated at 1 comprising a pair of relatively moving arcing contacts 2 and 3 and a pair of relatively moving isolating or disconnecting contacts 4 and 5, serially arranged with respect to each other. The arcing contacts 2 and 3 have been illustrated as a part of a fluid blast interrupting unit 6 which may be constructed in the manner disclosed and claimed in copending application, Serial No. 570,006, Boisseau and Beall, filed December 27, 1944, now Patent No. 2,444,765, and assigned to the same assignee as the present application. Interrupting head or unit 6 comprises an insulating chamber 7 within which relatively movable arcing or interrupting contacts 2 and 3 are mounted. Both contacts 2 and 3 have been illustrated as movable contacts biased to the closed position by means of springs 8 and 9, respectively. In the closed position of the circuit breaker shown in Fig. 1, contacts 2 and 3 are in electrical engagement and the contact 2 extends through a nozzle 10 while the contact 3 extends through a nozzle 11. Associated with contact 2 is a fluid motor comprising the piston 12. Similarly associated with the contact 3 is a fluid motor comprising the piston 13. Pistons 12 and 13 are reciprocal within cylinders suitably mounted in arc extinguishing chamber 7.

In order to interrupt the current flowing through arcing contacts 2 and 3 fluid under pressure is supplied from a source illustrated as a tank 14 through a blast conduit 15 to arcing chamber 7, conduit 15 being branched as indicated at 16 and 17 so as to supply fluid under pressure ahead of each nozzle 10 and 11, respectively. The flow of this fluid under pressure which is preferably air, is controlled by a blast valve generally indicated at 18 closely associated with tank 14. When blast valve 18 is opened contacts 2 and 3 are retracted through nozzles 10 and 11 and a blast of fluid through each nozzle quickly extinguishes the arc drawn between contacts 2 and 3. The fluid blast exhausts to atmosphere through conduit 19.

Since arcing or interrupting contacts 2 and 3 are of the so-called retractable pin-type which reclose as soon as fluid under pressure is shut off relative to arcing chamber 7, it is necessary to provide isolating or disconnecting contacts 4 and 5. Isolating contact 4 is indicated as a stationary contact suitably supported on an insulating support 20 and preferably electrically connected to a suitable circuit to be controlled as indicated at 21. Disconnecting or isolating contact 5, on the other hand, really comprises an isolating switch or contact arm pivotally mounted about a horizontal axis 22. Isolating switch 5 is the movable contact and the pivoted end thereof is provided with a bevel gear 23 which meshes with bevel gear 24 mounted on a rotatable shaft 25. Shaft 25 is rotated from the grounded supporting structure below through an intervening insulating column 26 rotatable therewith.

Isolating contact arm 5 is electrically connected to movable arcing contact 3 by means of a con-

ductor 27. Movable arcing contact 2 is connected with power line or circuit 28 in order to control the power flowing therein.

Blast valve 18 has been illustrated as comprising a valve member 29 connected by a valve stem 30 with the armature 31 of a solenoid including a winding 32. A suitable spring 33 normally biases valve member 29 to the closed position indicated in Fig. 1. Winding 32 for controlling the operation of blast valve 18 is connected to a source of control power 34 through the contacts 35 of an overload relay including a winding 36. Energization of winding 36 by a current of sufficient magnitude will cause bridging of contacts 35 with the consequent energization of winding 32 of the blast valve solenoid from source of control potential 34. Winding 36 of the overload relay is connected to the secondary winding 37 of a current transformer associated with power line 28. In the event of an abnormal current condition on power line 28, such as might be caused by a fault condition, winding 36 of the associated relay is energized sufficiently to cause contacts 35 to close whereupon blast valve 18 is opened and an arc is drawn and extinguished in arcing chamber 7.

It is obvious that after arcing contacts 2 and 3 have operated to interrupt the circuit, isolating contacts 4 and 5 must be separated if the circuit 30 is to remain open and this operation of isolating contacts 4 and 5 must occur before arcing contacts 2 and 3 have reclosed. In order to cause relative separation of isolating or disconnecting contacts 4 and 5 we have provided a second fluid motor generally indicated at 38, the term second fluid motor being applied to distinguish it from the fluid motors in interrupting unit 6. Fluid motor 38 comprises a cylinder 39 having mounted therein a piston 40 which is connected by rod 41 with a rack 42. Rack 42 is adapted to engage a spur gear 43 mounted on rotatable insulating column 26. It is obvious from Fig. 1 that when piston 40 is moved to the left, shaft 25 and bevel gear 24 are rotated so as to move disconnecting arm 5 to its open position. Rack 42 may also be connected by a connecting rod 44 with another fluid motor in the manner disclosed and claimed in copending application Serial No. 529,670, Boisseau, filed April 5, 1944, now Patent No. 2,445,558, and assigned to the same assignee as the present application.

In order to operate fluid motor 38 and consequently to cause relative separation of isolating or disconnecting contacts 4 and 5 cylinder 39 is connected with source 14 by conduits 45 and 46 and a switch controlling valve generally indicated at 47. Switch controlling valve 47, which is an opening valve, is preferably constructed in accordance with the arrangement disclosed and claimed in copending application Serial No. 565,835, now Patent No. 2,437,086, Frank and Kellar, filed concurrently with the present application and assigned to the same assignee as the present application. Essentially, switch opening valve 47 comprises a main valve member 48 connected to a piston 49 and biased to the closed position by means of a spring 50. When the valve member 48 is in the closed position indicated in Fig. 1, conduit 45 is connected to atmosphere through a port 51 which is closed by valve member 52 when valve member 48 is open. Opening valve 47 is of the balanced pressure type and is opened by operation of a pilot valve member 53 which opens the port 54 releasing to atmosphere the fluid under pressure acting on one side of the

piston 48 with the consequent opening of valve member 48.

The pilot valve member 53 of circuit breaker opening valve 47 is illustrated as being pneumatically operated by means of a piston 55 connected thereto which piston is reciprocal in a cylinder 55'. A spring 56 biases pilot valve member 53 of the circuit breaker opening valve 47 to the closed position.

Cylinder 55' of the fluid motor for operating pilot valve member 53 is connected to blast valve conduit 15 by means of a conduit 57, isolating switch reclosing interlock valve, generally indicated at 58 to be described in greater detail hereinafter, and conduit 59. Whenever blast valve 18 is open fluid under pressure will be admitted to conduit 57 and if isolating switch reclosing interlock valve 58 is open, as is indicated in Fig. 1, this fluid under pressure may pass through conduit 59 into cylinder 55' with the consequent opening of pilot valve member 53. The opening of pilot valve member 53 causes opening of the main valve member 48 of circuit breaker opening valve 47 and fluid under pressure flows through conduit 45 to fluid motor 38. In accordance with the disclosure of the above mentioned Frank and Kellar copending application circuit breaker opening valve 47 is preferably provided with means for maintaining the valve in the open position once it has opened until the isolating contacts 4 and 5 have opened. Since this forms no part of our invention it has been omitted for the purpose of simplifying the drawings.

As was mentioned above, a circuit breaker having serially connected interrupting and isolating contacts in which the interrupting contacts are fluid operated and normally biased to the closed position is inherently adapted to operate as a reclosing circuit breaker since the interrupting contacts automatically reclose upon cessation of the fluid blast. Accordingly, we have provided a control arrangement by means of which the circuit breaker 1 may be operated as a reclosing breaker. It will be understood by those skilled in the art that reclosing operation of the circuit breaker 1 may be obtained by preventing the isolating contact arm 5 from operating whereupon interrupting contacts 2 and 3 associated with interrupting unit 6 will interrupt the circuit and then will immediately reclose upon cessation of the interrupting blast.

In order to prevent contact arm 5 from opening whenever blast valve 18 is caused to open we have provided isolating switch reclosing interlock valve 58 which controls the operation of switch opening valve 47. Isolating switch reclosing interlock valve 58 comprises a normally open valve member 60 slidably mounted in a housing 61 and adapted to be electrically operated by a solenoid 62 including a winding 63. Whenever winding 63 is energized valve member 60 moves upwardly to block the flow through interlock valve 58 and consequently to switch opening valve 47. Solenoid 62 may, if desired, control a switch 64 which normally bridges contacts 65, the purpose of which will be described later.

By employing a normally open interlock valve 58 instead of one which normally blocks the passage to the switch opening valve 47 and which is arranged to be moved to its open position after a predetermined number of reclosures to effect a full switch opening operation, it will be apparent that our arrangement has the advantage that should the interlock valve or its

winding be inadvertently damaged and rendered inoperative, the breaker will simply effect a full switch opening operation in response to either a transient or sustained fault; whereas, in the case of the other mentioned arrangement, a damaged or frozen valve would preclude a full switch opening operation and serious damage to the equipment could ensue.

The reclosing-trip operation of a circuit breaker consists of two successive openings of interrupting contacts 2 and 3 followed by opening of the isolating contacts. It will be understood that the interrupting contacts might be opened and reclosed more than two times before the isolating contacts are opened. However, we prefer to provide only two successive operations of the interrupting contacts before the isolating contacts are operated, and to this end there is provided in accordance with our invention a pneumatic reclosing relay generally indicated at 66. This pneumatic reclosing relay controls the time which is permitted to elapse between the opening and reclosing of the interrupting contacts and furthermore conditions the reclosing control circuits for the opening operation of the isolating switch comprising contact arm 5 that sequentially follows the first reclosing operation if a persistent fault is present. Actually, pneumatic reclosing relay 66 performs four separate functions. First, it deenergizes the blast valve winding 32 by opening a normally closed switch 67 whereby the interrupting contacts 2 and 3 may reclose in response to a cessation of the fluid blast. Secondly, pneumatic reclosing relay 66 assures the establishment of a supplementary circuit for reenergizing blast winding 32 by closing a normally open switch 68, which is parallel or shunt with switch 67, within the short time interval between the instant when switch 67 deenergizes the blast valve winding 32 and before the arcing contacts reclose. With this arrangement if a fault persists the blast valve winding 32 will immediately be reenergized, the blast valve opened and the arcing contacts 45 operated to reinterrupt the circuit if overcurrent relay contacts 35 reclose. Thirdly, the pneumatic reclosing relay 66 assures that the isolating switch 5 is operated following a second quick successive opening operation of interrupting contacts 2 and 3 by opening a normally closed switch 69 which prevents reenergization of isolating switch reclosing interlock winding 63. Fourthly, the pneumatic reclosing relay 66 must restore the switches 67, 68 and 69 to their normal position indicated in Fig. 1 at the end of the pneumatic reclosing relay cycle, say approximately one second, in preparation for a possible repeat reclosing cycle.

Before describing the detailed features of the pneumatic reclosing relay 66, the electrical circuits controlled by switches 67, 68 and 69 will be described whereby the operation of pneumatic reclosing relay 66 may be understood more readily. The winding 32 of blast valve 18, the energization of which is controlled by the bridging of contacts 35, is actually connected in series with two switches, the opening of either being effective to cut off the blast valve winding circuit. The first of these is switch 67, of the reclosing relay 66, the opening of which determines the duration of the first blast, while the second is the auxiliary or cut-off switch 70 whose opening deenergizes the supplementary blast valve winding circuit and which determines the longer duration of the successive blast. To

those skilled in the art it will be understood from the above description that the closing of contacts 35 of the overload relay 36 merely initiates the opening of the blast valve due to the energization of coil 32 and that the precise closing instant of the blast valve is governed alternatively either by the opening of the cut-off switch 67 or by the opening of auxiliary cut-off switch 70. Therefore suitable means, not shown but examples of which are well known in the art, are provided for insuring that after the circuit of winding 32 has been completed by the closing of contacts 35 of relay 36, the subsequent opening of these contacts 35 does not effect the de-energization of the winding 32 until its circuit is opened either by the cut-off switch 67 or 70. It will be obvious from Fig. 1 that the circuit for energizing blast valve winding 32 may be traced from the positive side of potential source 34, through contacts 71 of auxiliary or cut-off switch 70, through switch 67 which normally engages contact 72, through blast valve winding 32 and the contacts 35 of the overload relay having a winding 36 to the negative terminal of control potential source 34.

A manually operated reclosing selector switch 73 is provided, which in the position indicated in Fig. 1 causes circuit breaker 1 to operate as a reclosing breaker. When in this position reclosing selector switch 73 compels winding 63 of isolating interlock valve 58 to be energized from source 34 upon closure or bridging of contacts 35. The energization circuit for winding 63 may be traced from the positive terminal of source 34 through switch 69 which normally engages contact 74, winding 63 of isolating interlock valve 58, reclosing selector switch 73, and contacts 35 of the overcurrent relay including winding 36 to the negative terminal of potential source 34. As long as winding 63 is energized the associated valve member 60 prevents operation of the switch controlling valve 47 so that isolating switch 5 remains closed and only the arcing contacts 2 and 3 are operated. On the other hand, when selector switch 73 has been moved to its other position so as to engage contact 75, the control circuit is conditioned for non-automatic reclosing service, for winding 63 can never be energized so that every time arcing contacts 2 and 3 are operated a sequential opening of the isolating contacts 4 and 5 inevitably accompanies a circuit interrupting operation.

Summarizing the above detailed explanation, it will be understood that the three sets of switch contacts controlled by the reclosing relay 66 operate in a predetermined sequence in which, firstly, the switch 67 opens to terminate the first interrupting blast thereby permitting automatic reclosure of the interrupting contacts 2 and 3. Secondly, the interlock cut-off switch 69 opens to open-circuit the winding 63 so that interlock valve 60 can no longer prevent the sequential opening of the isolating contacts 4 and 5 in the event that a second interrupting blast occurs due to a continuation of the line fault. Thirdly, switch 68 closes to establish a closed shunt path around the already opened switch 67, thereby permitting a second interrupting blast which, in this case, is terminated by the auxiliary or cut-off switch 70 that opens in accordance with the accompanying opening of the isolating contact arm 5.

The pneumatic reclosing relay 66 comprises a plurality of cylinders 71 and 78. A rather elaborate piston 79 is reciprocal in cylinder 71, while

an ordinary piston 80 is reciprocal in cylinder 78. Pistons 79 and 80 are interconnected by a plurality of links 81 and 82 and a lever 83 rotatable with a cam shaft 84. Link 82 connects piston 80 with one end of lever 83, while link 81 connects piston 79 with the other end of lever 83. With this arrangement the pistons 79 and 80 are interconnected so that when piston 79 is at the upper end of cylinder 71 piston 80 is at the bottom of cylinder 78. A spring 85 mounted in cylinder 78, the tension of which may be controlled by an adjustable means 86, normally biases the pistons 79 and 80 to the positions indicated in Fig. 1. A certain amount of limited adjustment of the initial piston position is afforded by link 82 which may comprise a screwed eye-bolt connection indicated at 87.

Speciably constructed piston 79 includes a port 88 leading from the upper face of the piston to an annular chamber 89 intermediate the ends of the piston. When fluid under pressure is admitted to cylinder 71 through restricting orifice 86 the pressure builds up slowly in bore 88 and annular chamber 89 until it overcomes the opposing force of spring 85 before the piston 79 begins to move slowly downward with regulated speed. After a short initial slow speed travel, piston 79 uncovers a port 91 tapped in the side wall of cylinder 71 which is illustrated as connected with an accumulator chamber 92. When annular chamber 89 is exposed to port 91 fluid under pressure must build up in chamber 92 before further movement of piston 79 will take place. In certain cases it may be desirable to dispense with accumulator chamber 92 and merely provide an orifice 91 to atmosphere in which case slower reclosing times are obtained. If faster reclosing times are desired port 91 may be dispensed with entirely. It is obvious that by providing an accumulator chamber the size of which may be varied, an orifice to atmosphere, or no port at all, widely varying travel-time characteristics of piston 79 may be secured.

In accordance with the disclosure of Fig. 1, at approximately two-thirds of the stroke of piston 79 port 91 is again blocked or closed by the upper portion of piston 79 so that in the cases where accumulator chamber 92 or an orifice to atmosphere is provided with a resulting hesitation of piston 79, speeding up of piston 79 then occurs to complete the piston stroke against the increasing force of return spring 85. The function of pneumatic reclosing relay 66 is to obtain an operating impulse from the fluid blast of the circuit breaker, which exists for a very short time such as a relatively few cycles of the alternating current of power line 28, and to give accurate and desired time control over a period of at least 60 cycles based only on the initial impulse. To this end pneumatic reclosing relay 66 is supplied with fluid under pressure from conduit 51 every time blast valve 18 is opened. In order that fluid under pressure for operating pneumatic relay 66 may be available for a period comparable with the operating cycle of pneumatic relay 66 even though fluid under pressure in conduit 51 exists for a very small fraction of this period, a time delay reservoir 93 is provided which is connected between conduit 51 and conduit 94 connected to orifice 90 in cylinder 71. A check valve 95 prevents the escape of fluid from time delay reservoir 93 back through conduit 51. A check valve 96 also may be provided for preventing fluid from flowing back from conduit 94

into reservoir 83 if desired. Preferably time delay reservoir 83 is provided with an adjustable escape port 87. By proportioning the volume of time delay reservoir 83 and the size of escape port 87 the length of the cycle of pneumatic relay 66 can readily be controlled.

It will be understood that an operating cycle of pneumatic reclosing relay 66 consists of a downward stroke of the piston 79 followed by its return stroke under the influence of spring means 85, the physical limits being determined by the positioning of adjustable means 86 within cylinder 78. During this cycle of operation of pneumatic reclosing relay 66 shaft 84, which in effect is a cam shaft, is rotated approximately 90 degrees from the position indicated in Fig. 1 to the position indicated in Fig. 2, and then returned to its initial position shown in Fig. 1 at which time the air pressure in time chamber or time delay reservoir 83 and in cylinder 77 has been dissipated.

In accordance with the four requirements specified for the reclosing relay of our invention, switches 67, 68 and 69 must be operated in a predetermined sequence during the down stroke of piston 79 and in a different manner during the up stroke of this piston. Accordingly we have illustrated switch 67 as pivotally mounted at 98 and biased to the closed position by means of a spring 99. Operation of switch 67 may be accomplished by a cam 100 adjustably mounted on shaft 84 and rotatable therewith. It is desired that switch 67 be opened early in the cycle of pneumatic reclosing relay 66, say approximately two cycles after piston 79 begins to move or probably some five cycles after winding 36 of the overload relay is energized. The rise 101 of cam 100 is adapted to engage a roller 102 associated with pivotally mounted switch 67 so that when cam 100 rotates in a counterclockwise direction as viewed in Fig. 1, roller 102 rises on cam surface 101 and switch 67 is opened. Reclosing of switch 67 occurs at the end of the reverse stroke of piston 79 when roller 102 rides down the cam rise 101. The arrangement described thus far performs the first requirement or the first function enumerated above for pneumatic relay 66.

In order to fulfill the requirements of the second and third functions of pneumatic relay 66 mentioned above, it is desirable that switches 68 and 69 are actuated a few cycles later than the opening of switch 67, the switch 69 conveniently being opened during the closing movement of switch 68. Respecting the fourth function, by arranging for the substantially simultaneous resetting of switches 67, 68 and 69 the reclosing circuits are restored to their original condition without hazard or loss of air that might result from a false operation in the event that the breaker is switched closed before the completion of the resetting process. Accordingly, switches 68 and 69 must operate at a different point on the return stroke than that at which they operated on the down stroke of piston 79. To accomplish this, switches 68 and 69 are mounted on a common support pivotally mounted at 103 which support is biased to the position indicated in Fig. 1 by spring means 104. Switches 68 and 69 are movable between contacts 76 and 74 so that they are in effect sequentially operable, the switch 69 opening before the switch 68 is closed, and the switch 68 opening before the switch 69 is closed. In accordance with our invention actuation of switches 68 and 69 is performed by a rockable

prop-type cam 105 pivotally mounted at 106 to a fixed support 107. This cam has a large opening in the center thereof (not shown in the drawing) through which shaft 84 may extend and of such a size as to provide sufficient clearance around shaft 84 so that adequate pivotal movement of cam 105 is permitted. When the cam 105 is rotated in a counter-clockwise direction from the position indicated in Fig. 1 to the position indicated in Fig. 2 it engages a roller 108 mounted on the pivotally mounted support for switches 68 and 69 and actuates the switches to the position indicated in Fig. 2 when the roller 108 moves upon the arcuate surface 109 of prop-type cam 105 as is clearly shown in Fig. 2. The switches 68 and 69 remain in the position indicated in Fig. 2 until the prop cam 105 is brought back to its original position at which moment the switch arm roller 108 drops off the prop cam surface 109. From the above description it will be obvious that either switch 67 or switch 68 is closed practically all of the time so that winding 32 is capable of being energized at any time there is trouble on the associated power line. Whether switch 67 or 68 is closed determines whether external switch blade 5 will be opened or not.

In order to actuate prop-type cam 105 at the proper time to open switch 69 and close switch 68 we provide a cam 110 adjustably mounted on cam shaft 84 and rotatable therewith. Cam 110 is preferably similar to cam 100 described above. Cam 110 is mounted closely adjacent to one side of prop-type cam 105 so that during rotation of cam shaft 84 and cam 110 a roller 111 on prop-type cam 105 is engaged by cam 110 and when roller 111 rides up the cam rise 112 of cam 110, as is indicated in Fig. 2, switches 68 and 69 are actuated to the positions indicated in Fig. 2, and are maintained in these positions due to the "downhill" curvature of cam surface 109 upon which roller 108 dwells even though cam 110 were reversely rotated and roller 111 was free of the high point of operating cam 110. Cam 110 is designated as the operating cam to distinguish it from a resetting cam 113 that also is adjustably mounted on cam shaft 84 but closely adjacent the other side of prop-type cam 105 so that prop-type cam 105 is mounted between cams 110 and 113. Resetting cam 113 is provided with a cam rise 114 for engaging a roller 115 mounted on prop-type cam 105 on the opposite side from where roller 111 is mounted. When the cam shaft, including resetting cam 113, is rotated in a clockwise direction as viewed in Fig. 2, the cam rise 114 engages roller 115 thereby rotating prop-type cam 105 back to its original position so that switches 68 and 69 are reset to the positions indicated in Fig. 1. By properly positioning resetting cam 113 on cam shaft 84 relative to cam 100 the switches 67, 68 and 69 may be reset at approximately the same time near the end of the return stroke of piston 79.

The return stroke of pneumatic reclosing relay 66 is much slower than the pressure stroke for actually in accordance with the preferred embodiment of our invention all three switches 67, 68 and 69 have operated within about one-sixth of a second or 10 cycles while the resetting of these switches does not occur until approximately one minute or 60 cycles later, cycles referring to an alternating current flowing in power line 28 having a frequency of 60 cycles. The following table is representative of the sequential order of operation of the various parts of an electric

circuit breaker constructed in accordance with our invention with reference to the time elapsed from the time of energization of overcurrent relay winding 36 for a typical reclosing operation:

Operation of Parts of Reclosing Breaker and Control Therefor	Elapsed Time in Cycles ¹
1 Winding 36 energized.....	.0
2 Contacts 35 bridged.....	1.0
3 Blast valve 18 opens.....	2.0
4 Circuit interrupted in chamber 7.....	2.9
5 Piston 79 begins to move.....	3.4
6 Switch 67 opens.....	5.2
7 Blast valve 18 closes.....	7.0
8 Switch 69 opens.....	8.5
9 Switch 68 closes.....	9.2
10 Circuit reclosed through contacts 2 and 3.....	15

IF FAULT PERSISTS

11 Winding 36 reenergized.....	13.0
12 Contacts 35 reclosed.....	14.0
13 Blast valve 18 reopens.....	15.0
14 Circuit re-interrupted in chamber 7.....	16.0
15 Isolating switch 5 opens.....	22.0
16 Auxiliary or blast cut-off switch 70 opens.....	22.5
17 Blast valve 18 recloses.....	24.5
18 Interrupter contacts 2 and 3 reclose.....	32.0
19 Switches 67, 68 and 69 reset.....	60.0-70.0

¹ Based on a 60 cycle per second system.

It will be understood that if after step 10 above the fault does not persist then steps 11 to 18 are eliminated and step 19 follows step 10.

In view of the detailed description included above the operation of the circuit breaker control arrangement including pneumatic reclosing relay 66 will be obvious to those skilled in the art. With the manual selector switch 73 in the position indicated in Fig. 1 a reclosing trip operation of circuit breaker 1 is initiated in response to an abnormal current condition on power line 28 causing overcurrent relay, including winding 36, to bridge contacts 35. Bridging of contacts 35 causes energization of blast valve winding 32 with the consequent opening of blast valve 18. At the same time winding 63 of isolating interlock valve 58 is also energized to close the passageway between conduits 57 and 59 whereupon switch opening valve 47 cannot be opened and consequently isolating or disconnecting contacts 4 and 5 remain closed. A blast of fluid under pressure in response to opening of blast valve 18 separates arcing contacts 2 and 3 and interrupts the circuit in chamber 7. As soon as blast valve 18 is opened pneumatic reclosing relay 66 is supplied with fluid under pressure and begins to function in a sequence set forth by the above mentioned table. Switch 67 is first opened to deenergize winding 32 whereupon the fluid blast is shut off and contacts 2 and 3 reclose the circuit under the influence of springs 8 and 9, respectively. Reclosing relay 66 continues to complete its cycle by virtue of the fluid stored in time delay reservoir 93 and after several more cycles have elapsed switch 69 is opened to deenergize winding 63 and consequently to reopen isolating interlock valve 58. Subsequently switch 68 is closed to complete a supplementary circuit for blast valve winding 32. If a system fault persists then contacts 35 will again be bridged as soon as arcing contacts 2 and 3 reclose the circuit whereupon blast valve 18 will again be opened. This time, however, switch opening valve 47 is supplied with fluid under pressure for interlock winding 63 is now open-circuited by the opened contact 69 of the pneumatic relay so that isolating contacts 4 and 5 are operated to the open

position, during which opening movement the blast valve is cut off by the opening of switch 70. Reclosing relay 66 continues to complete its cycle with the resetting of all the switches 61, 68 and 69 near the end of the cycle.

If the fault were only a temporary fault then contacts 2 and 3 are not re-opened because no successive blast is initiated and pneumatic reclosing relay 66 completes its cycle without any further operation of the contacts of circuit breaker 1. If selector switch 73 is moved to engage contact 75, isolating contacts 4 and 5 are opened each time that arcing contacts 2 and 3 are opened although subsequent thereto, because coil 63 now is open-circuited so that the interlock valve 58 remains open in the position shown and cannot respond, even in the event that contacts 35 close, to prevent operation of the switch opening valve 47.

The contacts 65 controlled by switch 64 prevent premature cut-off of the fluid blast by switch 67 during an operation in which isolating switch or external switch blade 5 is operated. In the interest of minimizing air or gas consumption, the blast valve is closed more quickly on reclosing operations than on those in which the isolating switch 5 operates. When solenoid 62 is not energized, contacts 65 remain closed, shunting switch 67 and maintaining blast valve winding 32 energized until auxiliary switch 70 opens. In this way a continuing blast of fluid is assured for maintaining the interrupting contacts open until external switch blade 5 is substantially open even though switch 67 might have been opened.

It will be apparent to those skilled in the art that our invention is not limited to the particular construction shown but that changes and modifications may be made without departing from the spirit and scope of our invention, and we aim in the appended claims to cover all such changes and modifications.

What we claim as new and desire to secure by Letters Patent of the United States is:

1. In an electric circuit breaker comprising co-operating arcing contacts and cooperating disconnecting contacts serially connected with said arcing contacts in an electric circuit, a source of fluid under pressure, means including a blast valve for supplying a blast of arc extinguishing fluid adjacent said arcing contacts to separate the same and interrupt the circuit, means responsive to an operating condition of said circuit for opening said blast valve and consequently said arcing contacts, means for opening said disconnecting contacts, an electrically controlled valve responsive to said operating condition of said circuit for rendering said means for operating said disconnecting contacts ineffective, time delay means responsive to the opening of said blast valve for causing said blast valve to reclose with the consequent reclosing of said arcing contacts, and means responsive to a continuance or recurrence of said operating condition and controlled by said time delay means for rendering said electrically controlled valve ineffective to prevent opening of said disconnecting contacts following a subsequent opening of said arcing contacts.

2. In an electric switch comprising a pair of relatively movable contacts connected to control an electric circuit, a source of fluid under pressure, means including a normally closed valve connected to said source of fluid for causing relative separation of said contacts, means responsive to an operating condition of said circuit for re-

leasing fluid capable of actuating said valve from said source, interference means responsive to said operating condition of said circuit for preventing said released fluid from actuating said valve, time delay means responsive to said release of fluid from said source for rendering said interference means ineffective after a predetermined delay, and means responsive to a continuance or recurrence of said operating condition and controlled by said time delay means for again releasing fluid from said source that is effective to open the valve of said first mentioned means thereby causing relative separation of said contacts.

3. In an electric circuit breaker comprising cooperating arcing contacts and cooperating disconnecting contacts serially connected with said arcing contacts in an electric circuit, a source of fluid under pressure, a blast valve connected to said source, means responsive to an operating condition of said circuit for opening said blast valve, means for opening said disconnecting contacts, an electrically controlled valve responsive to said operating condition of said circuit for rendering said means for opening said disconnecting contacts ineffective, time delay means including a fluid operated piston responsive to the opening of said blast valve for causing said blast valve to reclose, and means responsive to a continuance or recurrence of said operating condition and controlled by said time delay means for rendering said electrically controlled valve ineffective to prevent opening of said disconnecting contacts following a subsequent opening of said arcing contacts.

4. In an electric circuit breaker comprising cooperating arcing contacts and cooperating disconnecting contacts serially connected with said arcing contacts in an electric circuit, a source of fluid under pressure, means including a blast valve for supplying a blast of arc extinguishing fluid adjacent said arcing contacts to separate the same and interrupt the circuit, means responsive to an operating condition of said circuit for opening said blast valve and consequently said arcing contacts, means for opening said disconnecting contacts, an electrically controlled interlock valve responsive to said operating condition of said circuit for rendering said means for opening said disconnecting contacts ineffective, time delay means including a pair of pistons interconnected by a linkage mechanism and responsive to the opening of said blast valve for causing said blast valve to reclose with the consequent reclosing of said arcing contacts, and means responsive to a continuance or recurrence of said operating condition and controlled by said time delay means for rendering said means for opening said disconnecting contacts effective to open said disconnecting contacts following a subsequent opening of said arcing contacts.

5. In an electric circuit breaker comprising cooperating arcing contacts and cooperating disconnecting contacts serially connected with said arcing contacts in an electric circuit, a source of fluid under pressure, a blast valve connected to said source, means responsive to an operating condition of said circuit for opening said blast valve, means for opening said disconnecting contacts, an electrically controlled valve responsive to said operating condition of said circuit for rendering said means for opening said disconnecting contacts ineffective, time delay means including cam operated switches controlled by a fluid operated piston responsive to the opening of said blast valve for causing said blast valve

to reclose, and means responsive to a continuance or recurrence of said operating condition and controlled by one of said cam operated switches for rendering said electrically controlled valve ineffective to prevent opening of said disconnecting contacts following a subsequent opening of said arcing contacts.

6. In an electric switch comprising a pair of relatively movable contacts connected to control an electric circuit, a source of fluid under pressure, a fluid motor for producing relative movement between said contacts, a valve for controlling the flow of fluid between said source and said fluid motor, means responsive to an operating condition of said circuit for releasing fluid from said source capable of causing operation of said valve, and a normally open interlock valve arranged to close in response to said operating condition of said circuit for preventing the released fluid from actuating said valve for a predetermined time after the occurrence of said operating condition.

7. In an electric circuit breaker comprising cooperating arcing contacts and a disconnecting switch serially connected with said arcing contacts in an electric circuit, a source of fluid under pressure, means including a blast valve for supplying a blast of arc extinguishing fluid adjacent said arcing contacts to separate the same and interrupt the circuit, means responsive to an operating condition of said circuit for opening said blast valve and consequently said arcing contacts, a fluid motor for opening said disconnecting switch, a switch controlling valve for controlling the flow of fluid between said source and said fluid motor, an electrically controlled interlock valve responsive to said operating condition of said circuit for rendering said switch controlling valve ineffective to supply fluid to said fluid motor to open said disconnect switch, time delay means including a pair of pistons interconnected by a linkage mechanism and responsive to the opening of said blast valve for causing said blast valve to reclose with the consequent reclosing of said arcing contacts, and means responsive to a continuance or recurrence of said operating condition and controlled by said time delay means for rendering said interlock valve inoperative thereby rendering said switch controlling valve effective to cause said disconnecting switch to open following a subsequent opening of said arcing contacts.

8. In an electric switch comprising a pair of relatively movable contacts connected to control an electric circuit, a source of fluid under pressure, a fluid motor for producing relative movement between said contacts, a switch controlling valve for controlling the flow of fluid between said source and said fluid motor, means responsive to an operating condition of said circuit for releasing energy capable of causing operation of said valve, and means responsive to said operating condition of said circuit for preventing the application of said released energy to said switch controlling valve for a predetermined time after the occurrence of said operating condition.

9. In combination with an electric circuit breaker having a pair of interrupting contacts and a pair of serially connected isolating contacts, means for controlling the operation of said interrupting contacts and said isolating contacts in a predetermined sequence, comprising a pneumatic motor having a piston and associated cylinder, a cam shaft connected to said piston and rotatable upon movement of said piston, means

including an annular chamber defined by said piston and cylinder for delaying the initial movement of said piston, a fluid reservoir in communication with said cylinder through an opening therein intermediate the ends thereof, said reservoir being effective while said chamber and said opening are in registry to slow down the operating movement of said piston after said initial movement thereof, means controlled by the position of said cam shaft for regulating the sequential operation of said isolating and said interrupting contacts, and means for controlling the supply of fluid under pressure to said motor to control the operation thereof.

10. In combination with an electric circuit breaker having a pair of interrupting contacts and a pair of serially connected isolating contacts, means for controlling the operation of said interrupting contacts and said isolating contacts in a predetermined sequence, comprising a pneumatic motor having a piston and associated cylinder, means connected to said piston and operable in response to movement of said piston to regulate the sequential operation of said interrupting contacts and said isolating contacts, means including an annular recess in said piston for delaying the movement of said piston during the initial portion of an operating stroke, means defining an opening in said cylinder for slowing down said piston when said recess registers with said opening during a subsequent portion of the operating stroke of said piston, and means for controlling the supply of fluid under pressure to said motor to control the operation thereof.

11. In combination with an electric circuit breaker having a pair of interrupting contacts and a pair of serially connected isolating contacts, means for controlling the operation of said interrupting contacts and said isolating contacts in a predetermined sequence, comprising fluid operated means, a cam shaft connected to said fluid operated means and rotatable in response to operation of said fluid operated means, a plurality of cams on said cam shaft, a plurality of switches operated by said cams in a predetermined sequence for one direction of rotation of said cam shaft, means for substantially simultaneously resetting said switches during the other direction of rotation of said cam shaft, means controlled by said switches for controlling the sequential operation of said interrupting and said isolating contacts, and means for controlling the supply of fluid under pressure to said fluid operated means to control the operation thereof.

12. In combination with an electric circuit breaker having a pair of interrupting contacts and a pair of serially connected isolating contacts, means for controlling the operation of said interrupting and said isolating contacts, comprising fluid operated means, a cam shaft connected to said fluid operated means and rotatable in response to operation of said fluid operated means, a first cam on said cam shaft, a first switch operated by said first cam, a second switch, a second cam having limited pivotal movement relative to said cam shaft for controlling said second switch, a pair of cams fixedly mounted on said cam shaft closely adjacent said

second cam, one of said pair of cams rendering said second cam effective to operate in a particular manner said second switch for one direction of rotation of said cam shaft, the other of said pair of cams rendering said second cam effective to operate in a reverse manner said second switch, said cams being so arranged on said cam shaft that said first and second switches are operated in a predetermined sequence for one direction of rotation of said cam shaft and substantially simultaneously operated for the other direction of rotation of said cam shaft, means controlled by said switches for controlling the sequential operation of said interrupting and said isolating contacts, and means for controlling the supply of fluid under pressure to said fluid operated means to control the operation thereof.

13. In combination with an electric circuit breaker having a pair of interrupting contacts and a pair of serially connected isolating contacts, means for controlling the operation of said interrupting contacts and said isolating contacts in a predetermined sequence, comprising fluid operated means, a cam shaft connected to said fluid operated means and rotatable in response to operation of said fluid operated means, a first cam on said cam shaft, a first switch operated by said first cam, a second switch, a second cam having limited pivotal movement relative to said cam shaft for controlling said second switch, a pair of cams fixedly mounted on said cam shaft closely adjacent said second cam, one of said pair of cams rendering said second cam effective to open said second switch for one direction of rotation of said cam shaft, the other of said pair of cams rendering said second cam effective to close said second switch, said cams being so arranged on said cam shaft that said first and second switches are opened in a predetermined sequence for one direction of rotation of said cam shaft and substantially simultaneously closed for the other direction of rotation of said cam shaft, means controlled by said switches for controlling the sequential operation of said interrupting and said isolating contacts, and means for controlling the supply of fluid under pressure to said fluid operated means to control the operation thereof.
